OF D 16,107

DESIGN.

—o—

A. L. HALLIDAY.

CARPET.

No. 16,107.

Patented May 26, 1885.

UNITED STATES PATENT OFFICE.

ARTHUR L. HALLIDAY, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 16,107, dated May 26, 1885.

Application filed February 13, 1885. Term of patent 3½ years.

To all whom it may concern:

Be it known that I, ARTHUR L. HALLIDAY, a resident of Yonkers, in the county of Westchester and State of New York, have invented and produced, by my own industry, genius, efforts, and expense, a new and original Design for a Carpet, of which the following is a full description, in connection with the accompanying photograph, which represents a face view of my new design for a carpet.

This invention relates to a new ornamentation of the face of a carpet, oil-cloth, or an analogous fabric.

In the accompanying photograph are represented the various parts which enter into my new design.

A is a figure of fanciful and peculiar outline, many of the lines being straight, especially those on the under side, others being curved, especially those on the upper side. In the converging lower sides of figure A are L-shaped recesses, as shown.

B is another figure of substantially the same outline as the figure A.

25 Between the figures A and B is an elongated rosette, C, of scalloped outline, forming button-shaped projections, said rosette having its greatest width at one side of its center, and containing six smaller figures, as shown.

30 D is another elongated rosette, resembling the figure C, but differing therefrom in minor details.

Between the figures B and D are placed the figures E and F, which are of the form shown—that is to say, the figure E is an irregular polygon with dotted line within its border, and the figure F is a rosette with claw-like prongs at its ends, and with a square surrounded by eight small rosettes in its center.

40 Between the figures B and C are placed the figure G, consisting of two rhomboids that cross each other at an obtuse angle, the double oval rosettes H H, and the hexagonal figure I, having angular projections embracing it, as shown.

45 Between the figures A and C are placed the

figures J, L, K, M, and O. The figure J is a rhomboid with curvilinear wings on two of its converging sides. The figure L is cross-shaped, each end of the cross being T-shaped, squares having inwardly-projecting tails all parallel to one another being placed in the angles of the cross. Each figure O is of the form of an oblique cross inclosing five rhomboidal spaces.

Below the figure D is the figure P, which is composed of four unequal rosettes grouped around a central diamond-shaped figure, and also the star-shaped figure Q, the center of which is an oval rosette, around which are grouped four fanciful leaves and intervening spear-like projections.

I claim—

65

1. The design for a carpet, the same consisting of the figure A, having the peculiar outline and the L-shaped recesses in the lower side, substantially as shown.

2. The design for a carpet, the same consisting of the figure C, having scalloped outline and button-shaped projections, and having its greatest width at one side of the center, substantially as shown.

3. The design for a carpet, the same consisting of the figure E, substantially as shown.

4. The design for a carpet, the same consisting of the figure F, substantially as shown.

5. The design for a carpet, the same consisting of the figure I, substantially as shown.

6. The design for a carpet, the same consisting of the figure J, substantially as shown.

7. The design for a carpet, the same consisting of the cross-shaped figure L, embracing squares that have parallel tails, substantially as shown.

8. The design for a carpet, the same consisting of the figure P, substantially as shown.

9. The design for a carpet, the same consisting of the figures A, B, C, D, E, F, G, H, I, J, K, L, M, N, O, P, and Q, substantially as shown.

ARTHUR L. HALLIDAY.
